(57) **CLAIM**

The ornamental design for a bench top x-ray fluorescence (XRF) instrument, herein as shown and described.

DESCRIPTION

FIG. 1 is an isometric view of a bench top x-ray fluorescence (XRF) instrument showing my new design.

FIG. 2 is a front elevation view of the bench top x-ray fluorescence (XRF) instrument.

FIG. 3 is a right-side elevation view of the bench top x-ray fluorescence (XRF) instrument.

FIG. 4 is a rear elevation view of the bench top x-ray fluorescence (XRF) instrument.

FIG. 5 is a bottom plan view of the bench top x-ray fluorescence (XRF) instrument.

FIG. 6 is a left-side elevation view of the bench top x-ray fluorescence (XRF) instrument; and,

FIG. 7 is a top plan view of the bench top x-ray fluorescence (XRF) instrument.

The broken lines shown in the drawings are for the purpose of illustrating portions of the article that form no part of the claimed design.
